UNITED STATES PATENT OFFICE.

ROBERT W. GENUNG, OF BLOOMING GROVE, NEW YORK.

LIFTING-JACK.

Specification of Letters Patent No. 11,298, dated July 11, 1854.

To all whom it may concern:

Be it known that I, ROBERT W. GENUNG, of Blooming Grove, in the county of Orange and State of New York, have invented a new and useful Improvement in Lifting Jacks; and I do hereby declare that the following is a full, clear, and exact description of the same, reference being had to the accompanying drawings, forming part 10 of this specification, in which—

Figure 1, is a side elevation of a lifting jack with my improvements. Fig. 2, is a front elevation of the same. Fig. 3, is a back view.

15 Similar letters of reference in each of the several figures indicate corresponding parts.

The nature of my invention consists, 1st, in a peculiar and simple manner of making the fulcrum of the lifting lever capable of 20 being adjusted so as to allow the rack bar to descend freely after it has been raised to the desired height. By this arrangement, the lever will also be always kept in its place ready for use, and will, (when ad- 25 justed so as to allow the rack bar to de- scend), be effectually prevented, without the necessity of holding it by the hand, from coming in contact with said bar until moved by the hand of the operator into its proper 30 position for lifting the same.

To enable others skilled in the art to make and use my invention, I will proceed to de- scribe its construction and operation.

A, represents the guide frame in which 35 the lifting rack bar is secured, and slides up and down freely, in the ordinary manner, or as represented in the drawing.

B, is the swinging pawl for stopping the 40 rack bar from falling while it is being raised. This pawl is made and arranged slightly different from the present mode, as will be evident from the drawing, it having two ears, α , α , cast in its upper end, and being secured by said ears to the upper ex- 45 tremity of the frame, A, by the fulcrum pin, b. By thus constructing the pawl and arranging it, it will be seen that the rack bar is capable of passing up between the ears of the same, and serves as a stop to

prevent it being thrown back out of opera- 50 tive position.

C, is the lifting lever, it is constructed as shown in the drawing, and has its fulcrum resting loosely in the bearings, d, d. In each of these bearings, a semi-circular 55 slot, e, is cast, for the fulcrum to play in freely as the lever is thrown in and out of contact with the rack bar. This slot is divided at its center by the partition f, so as to form two smaller semi-circular rests, 60 g, g', for the fulcrum of the lever to rest in alternately. By thus forming the slot, e, and dividing it, it will be evident from the drawing, that the lever can be adjusted with ease, so as to be in or out of contact with the 65 rack bar, and when thrown out of contact, its fulcrum will rest in the slot, g', as shown in red, and be held there by the partition, f, and prevented from getting in contact with the bar, while falling. The partition, f, 70 also keeps the lever in contact with the bar while lifting, and prevents its fulcrum slipping or changing its position, and allowing the bar to fall at the time when the pawl has no hold upon it. 75

All necessity of holding the lever in the hand while it is adjusted for letting the bar fall, is avoided, as the partition, f, prevents its fulcrum from shifting, and allowing the lever to get in contact with the bar. It is 80 the semi-circular slot, and the two smaller semi-circular fulcrum rests forming part of said slot that constitute the gist of my invention.

What I claim as my invention, and de- 85 sire to secure by Letters Patent, is:—

Making the lever capable of being ad- 90 justed so as to be thrown in and out of contact with the rack bar with facility and ease, and retaining it securely in its place after being adjusted, by providing the bearings, d, d', with a curved slot, e, and two semi- circular fulcrum rests, g, g', substantially as herein described, and shown in the drawing.

ROBERT W. GENUNG.
